ANTISLIP DEVICE

Clarence J. Goodman, Millburn, N. J.

Application January 30, 1934, Serial No. 708,939

5 Claims. (Cl. 36—7.7)

This invention has for an object the provision of novel means capable of being readily attached to shoes and adapted for effectively preventing slipping of the wearer. The invention has been 5 developed particularly for the field of golf and has proven highly efficient for enabling the practice of the game without danger of slipping on wet ground. It at the same time avoids the expense of obtaining special shoes with spiked soles. The 10 devices provided by this invention may furthermore be readily removed without requiring changing to other shoes after the game is completed. The invention further provides an anti-slip golfing attachment simple in construction, highly reliable in action, and comparatively inexpensive to 15 manufacture. A feature of the invention resides in an anti-slip device including novel means especially effective in maintaining anti-slip projections firmly attached in operative position to 20 the shoes. This, moreover, is accomplished without requiring high shoes to be worn and without necessitating the engagement of any part of the 25 attaching means with the stockings of the wearer. Other features and advantages of the invention will be hereinafter described and claimed.

In the accompanying drawing:

Fig. 1 is a view in side elevation showing a device embodying my invention applied to a shoe.

Fig. 2 is a bottom view showing the device and 30 shoe of Fig. 1.

Fig. 3 is a top view thereof.

Fig. 4 is a perspective view of the device.

Fig. 5 is a vertical sectional view on line 5—5 of 35 Fig. 4.

Referring to the drawing, the device illustrative of my invention is shown as comprising a member 2 of leather or other suitable material, through which anti-slip projections 3 extend. I prefer that said member be composed of relatively heavy leather such as "saddle leather", having substantial wear resisting qualities as well as considerable pliability though it will be apparent that other material may be utilized. Over the member 2 there extends a member 4, which may 40 be of leather, webbing, or other material, from opposite ends of which there extend the flexible strap elements 5, 6. Element 5 is shown as cut from the same piece of material as said member 4, and strap element 6 as stitched thereto, though 45 both elements 5, 6 may be cut from the same material as member 4, or both may be obtained from separate material and stitched or otherwise secured to said member.

The bottom member 2 is shown extended rearwardly at 2' and provided with a loop 7, which

may be conveniently formed by bending over an end of said extended portion of the member 2 and stitching the free end thereof to said extension.

The device is applied to a shoe 8 as illustrated in Figures 1, 2, and 3. With the shoe resting on the member 4, the strap 5, which carries at one end a buckle 9, passes over the top of the shoe, and thence downwardly beneath said shoe, and through the loop 7 which lies under the shoe as shown. The strap 6 is now drawn over the top 10 of the shoe, in the opposite direction to strap 5, then under the shoe and through the loop 7 (again in the direction opposite to strap 5), and thence around the heel portion 10 of the shoe to the side 15 of the shoe at which the buckle 9 is located. Strap 15 6 is now passed through said buckle and drawn tightly around the heel portion of said shoe, whereupon the tongue 9' of the buckle is engaged with the appropriate one of a series of holes 6' in the strap 6. The device is now firmly engaged 20 with the shoe and is securely maintained in position thereon.

It will be seen that the straps 5 and 6 extend over the top of the shoe adjacent the instep, and that, in cooperation therewith, said straps prevent movement of the member 2 toward the heel. Also, the straps 6 in passing around the heel portion 10 of the shoe, effectively precludes forward movement of said member. It will be noted that the straps, in maintaining the member 2 in position, react upon and cooperate with the top, bottom and heel portion of the shoe, with the resultant attainment of an especially reliable attachment. It will further be observed that no more than two straps are required, with consequent simplicity of construction.

While the projections 3 may take any suitable form, those disclosed by way of example are shown as rivets. As illustrated in Fig. 5, each rivet may pass through both members 2 and 4, 40 with the head 3' of the rivet bearing upon member 4. Washers 11 of brass or other suitable material may surround each rivet, and bear on the under side of member 2, the lower end 3'' of the rivet being expanded as shown to force said washer tightly against said member 2. The rivets 3 thus serve not only as anti-slip projections but also to fasten the members 2 and 4 together.

The member 4 may, as shown, be of sufficient length that its portions 4', 4'' extend around the sides and partly over the top of the shoe. Said portions 4', 4'' may be flared as illustrated to merge into the outlines of the straps 5, 6.

It will be furthermore apparent that the device above described is readily attachable to low 55

shoes, and that no part of the straps engage the stockings of the wearer. The wearing of high shoes is hence unnecessary. The device moreover is readily detachable whenever desired, and may be quickly folded into a small space for transportation.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

15 I claim:

1. An anti-slip device adapted for removable attachment to a shoe, said device comprising a member having downwardly extending projections and adapted to underlie the sole of the shoe, a loop element connected to said member for underlying said shoe, and strap means passing from said member over the top of the shoe, through said loop element, and around the heel portion of the shoe, for securing said member to said shoe.
2. An anti-slip device adapted for removable attachment to a shoe, said device comprising a member having downwardly extending projections and adapted to underlie the sole of the shoe, a loop element connected to said member, a flexible element extending from one side of said member and arranged to pass over the top of the shoe and through said loop element, and another flexible element extending from the opposite side of said member for passing over the top of the shoe, through said loop element, and around the

heel portion of the shoe to meet the first mentioned flexible element, and means for securing said flexible elements together.

3. An anti-slip device adapted for removable attachment to a shoe, said device comprising a leather member having downwardly extending projections and adapted to underlie the sole of the shoe, a loop element connected to said member for underlying the shoe, and flexible means extending from said member over the top of the shoe, through said loop element beneath the shoe, and around the heel portion of the shoe, for securing said element to the shoe.

4. An anti-slip device adapted for removable attachment to a shoe, said device comprising a member having downwardly extending projections and adapted to underlie the sole of said shoe, a loop element connected to said member and underlying the shoe, and flexible means comprising a strap extending from said member over the top of the shoe, through said loop element to the rear end of the shoe for securing said member to said shoe.

5. An anti-slip device adapted for removable attachment to a shoe, said device comprising a member having downwardly extending projections and adapted to underlie the sole of said shoe, a loop element connected to said member and underlying the shoe, and flexible means comprising a pair of straps passing over the top of the shoe and through said loop element for securing said member to said shoe, one of said straps extending to the heel portion of the shoe.

CLARENCE J. GOODMAN. 35
